UNITED STATES PATENT OFFICE.

JOHANN CARL MÜLLER, OF DRESDEN, GERMANY, ASSIGNOR TO "UNIVERSELLE" CIGARETTEN-MASCHINEN-INDUSTRIE SYSTEM OTTO BERGSTRÄSSER AKTIEN-GESELLSCHAFT, OF DRESDEN-LOBTAU, GERMANY, A CORPORATION OF GERMANY.

APPARATUS FOR COVERING THE TIP ENDS OF CIGARETTE-PAPER WITH GOLD-LEAF.

1,114,507.

Specification of Letters Patent.

Patented Oct. 20, 1914.

Application filed October 14, 1911. Serial No. 654,750.

To all whom it may concern:

Be it known that I, JOHANN CARL MÜLLER, a subject of the German Emperor, and residing in Dresden, in the Kingdom of Saxony, Germany, have invented certain new and useful Improvements in Apparatus for Covering the Tip Ends of Cigarette-Paper with Gold-Leaf.

My invention relates to the separation of the leaves of gold which are to be used on the cigarette mouth-pieces from the compound strip which is formed into a continuous roll; and further, to the attachment of the separated leaf of gold to the strip of cigarette-paper.

The strip of covering material, consisting of gold leaf, is as usual wound into a continuous roll in connection with an underlying strip of wrapping-paper. By means of my invention I separate the covering gold leaf, without cutting the underlying strip with the knife used therefor. And afterward I bring the separated leaf on to the place of the continuous and continuously-moving strip of cigarette paper, (already prepared with adhesive material for this purpose) by holding this portion of the strip still for a short period of time, without, however, interrupting the movement of the entire strip.

As regards the separation of the covering leaf—it has been long known how to effect this by a draw cut, without cutting through the underlying strip. By this operation the knife was pressed down only so far as to cut the covering material, without cutting the underlay. The extremely exact adjustment of the knife which is here necessary, is very difficult to effect, and can take no account of any inequalities in the underlying - strip. When, however, this underlying-strip is injured at any such place, it tears, and cannot serve further to bring the cut-off leaf to the gummed portion of the strip of cigarette-paper.

According to my invention, the knife is not positively guided, but this is effected by its own weight or by the action of a spring. Thereby the knife exerts on the material which is to be cut only that amount of pressure which is necessary to separate the covering gold-leaf, and that where irregularities in thickness etc., of the underlying strip ex-

ist, the knife can give way to the requisite degree. Naturally, either the weight of the knife itself, or the force of the spring which regulates its pressure, can be regulated minutely and exactly. After the separation of the leaf it must be gummed to the continuous and regularly continuously-moving strip of cigarette-paper; that is, this strip must be covered at proper distance apart with covering leaf. In order to effect this, the downward-moving strip of cigarette paper must temporarily remain motionless in the pressing device; that is, the portion which is to be gilded must remain motionless for a short period of time. My invention enables the portion of the strip in question to remain motionless in the pressing appliance, while at the same time permitting continuous, uninterrupted motion of the wrapper-strip to and from the portion to be covered or gilded; a result which is advantageous from the standpoint of safety against the breaking of the delicate strip of cigarette-paper at the time of approach.

The stopping of the portion of the strip in question is accomplished in such a manner that a relative shifting between the strip and the feed-rolls is effected. For this purpose there are two feed-rolls on a carriage, which is regularly reciprocated by a suitable mechanism, and also a non-reciprocating feed-roll. By this means there is formed in the strip of cigarette-paper a U-shaped loop or bight.

The new device is represented on the accompanying drawing in two different forms of construction, in both of which the same reference-letters and numerals are employed, and in which—

Figure 1 is a side-view, partly in longitudinal section, Fig. 2 is a vertical transverse section on the line 2—2, of Fig. 1, Fig. 3 is a detail side and top-view of the cam-roller shown in Fig. 2, and Fig. 4 is a side-view of another form of construction.

The roll A is formed in the usual manner of a strip of covering gold-leaf and an underlying strip of ordinary paper. The covering-strip is fed over a horizontal table B; from this the underlying strip C is fed over a roll D in downward direction. The feed motion of the underlying strip C, and with it of the covering gold-leaf is effected

by the eccentric pin F and the roll G. The separation of the gold-leaf from the underlying strip takes place on the table B. This separation is effected by the knife a, which is screwed to the front-end of the knife-holder b. The latter turns about the horizontal shaft c, which is screwed to the frame H at one end of the machine; the knife-holder is laterally shiftable on the horizontal axle c. The knife-holder is constantly pressed by a helical spring d, which is wound about the axle c, toward the part H of the frame, that is, in the direction of the arrow, shown in Fig. 2. On the hub of the knife-holder is arranged a semi-annular cam e which projects downwardly. Against this cam abuts the inner-end of a pin f, which is horizontally shiftable in a sleeve of the part H of the frame, as shown in Fig. 2. A horizontally-shifting motion of the knife-holder b against the pressure of the spring d is imparted by means of a roller g which acts intermittently against the outer end of the pin f. This roller g is journaled on a disk h, which is formed into a spur-wheel at its circumference and which is rotated from the driving-shaft of the machine. The roller g is placed rotatably on the end of a screw-bolt g', which is screwed into a cylindrical socket attached to the disk h by means of the plate g² and suitable fastening-screws, as shown in Figs. 2 and 3.

The movement of the pin f, which at the same time effects the shifting of the knife a over the covering-strip of gold-leaf, takes place at that instant of time, when the covering-strip is in a state of rest. The pressure of the knife on the covering-strip is determined only by the weight of the knife itself, and is so calculated that during its lateral motion the knife exerts a drawcut through the covering-strip of gold-foil only, but not through the underlying strip of ordinary paper.

After the separation of the covering-strip of gold-leaf has taken place, it is united with the tip-end of the strip of cigarette-wrapper E, which has been covered locally for that purpose with adhesive material. This strip E runs over the guide-roll 1 and is in the usual manner covered with adhesive material while passing between the roll 2 and the carrier 3 for the adhesive material, and then conducted over the guide-rolls 4, 5 and 6. The adhesive material is supplied to the surface of the carrier 3 at each rotation of the same in the usual manner by an adhesive transmitting contact-roll (not shown). At the emerging point there is effected an intermittent movement of the strip E by any desired means. The guide-rolls 4 and 5 are journaled on the carriage 7, which by appropriate mechanism is reciprocated to a regulatable extent. This re-

ciprocation takes place at the same speed as that of the strip of cigarette-wrapper and is accomplished in any suitable manner.

In the neighborhood of the loop or bight formed by the strip of cigarette-paper between the rolls 4, 5 and 6, is located a cutting-table B. Over this runs, as already described, the continuously-moving compound strip consisting of the covering strip of gold-leaf and an underlying strip of ordinary paper. The pieces of gold-leaf separated by the knife a remain on the underlie, and arrive at the end-portion of the table B, above which an intermittently-reciprocated presser-piece 15 is arranged. As soon as the carriage 7 has been moved with the roll 4 toward the left the presser-piece 15 is lowered and presses the strip of cigarette-paper with its gummed portion on the table B on which the gold-foil has been placed. The gold-foil adheres thereby to the cigarette-paper. The presser-piece is then moved upward again so as to clear the space for the return-motion of the carriage 7 and its roll 4. Any suitable mechanism for reciprocating the presser-piece 15 at the proper time may be employed.

In the form of construction, shown diagrammatically in Fig. 4, the upper shiftable roll 4 assumes the function of the presser-piece 15, which is dispensed with, as the roller 4 is rolled over the layers of underlying paper, covering-strip of gold-foil and cigarette-paper, then moving over the cutting-table B. In this case an oscillating movement of the table B against the roll 4, and a corresponding shifting is required, in order that after the covering of the tip-end of the cigarette-paper which is to be gilded, there may take place a relative clearance between the table B and the roll 4, to permit the free passage of the strip of cigarette-paper and the covering-strip of gold-foil. The cutting-table B is therefore made movable about the pin 16, and is lifted from time to time into contact with the roll 4 by the cam 17 and pin 18. The table B is lowered again so that the combined strip of cigarette-paper and layer of gold-foil can be moved forward freely.

When the carriage 7 moves to the left with the same speed as the unintermittently-moving strip E, the following occurs: The U-shaped loop or bight, which is formed by the inward motion of the strip E by the rolls 4 and 5, is moved to the left, which occasions the shifting of the lower portion of this loop, the length of which is naturally limited by the non-variable distance between the rolls 4 and 5 as far as it consists of newly-arriving strip-material, over the cutting-table B.

Over the roll 5 the strip E passes at the same rate of speed as that of the newly-arriving looped portion of the cigarette-

paper. As now, according to the form of construction shown in Fig. 1, the length of the strip between the rolls 4 and 5 is greater than the stroke or movement of the carriage, 5 the middle portion of the strip remains motionless at certain intervals; so that the presser-piece 15 can press this part of the strip against the cutting-table B.

In the construction shown in Fig. 4, the 10 operations are different from those just described. As here the roll 4 effects at the same time the transfer, by rolling on, of the covering material, it is not necessary to have, when the carriage 7 returns, a non-moving 15 loop of considerable extent between the rolls 4 and 5; the distance between the rolls 4 and 5 need not be greater than the stroke of the carriage.

The regular feed of the strip of cigarette- 20 paper may take place without hindrance, because the roll 5 approaches the roll 6 with the same speed as that of the strip; so that the downward movement of the strip can take place on account of the shortening of 25 the loop between the rolls 6 and 5. Also the inward feed of the strip can take place regularly, because its approach corresponds to the movement of the roll 4 toward the left.

When the carriage 7 returns (that is, 30 moves to the right in the drawing) a double length of strip will approach; as at this period the roll 4 moves toward the approaching strip. This double forward feed is, however, taken up by the lengthening of 35 that portion of the strip between the rolls 5 and 6; the strip at the same time receding uninterruptedly from the roll.

At its front end the carriage 7 is provided with an oblique surface; and at the 40 front end of the knife-holder there is a roll 2, which runs on the oblique surface of the carriage. By this means, after the covering-leaf is separated, the knife-holder is lifted above the table B. After this has 45 taken place, the table B, over which the covering material passes, sinks. During this downward movement, which is effected by the cam disk 17 and the roll 18, the forward feed of the covering material takes 50 place; at the same time the carriage 7 moves back, and the knife-holder returns downward to the position shown in Fig. 1, for cutting off the next covering-piece of gold-foil.

55 Claims:

1. An apparatus for covering the tip-ends 60 of strips of cigarette-paper with gold-leaf, which comprises a supporting table, means for feeding the gold-leaf with its underlying layer over said table, means for feeding a strip of cigarette-paper, means for supplying an adhesive to the tip-end of said cigarette-paper, and an intermittently-oscillating and laterally-shiftable knife for imparting a draw-cut to the knife for severing the

gold leaf without injury to the underlying paper.

2. In an apparatus for covering the tip-ends of strips of cigarette-paper with gold-foil, the combination, of an intermittently-oscillating table, means for feeding the gold-leaf with its underlying layer of paper over the table, an oscillating knife-holder, having a cutting knife at its outer end, means for laterally-shifting said knife-holder on its shaft for moving the knife by a draw-cut over the gold-leaf for severing it without injuring the underlying paper. 70

3. In an apparatus for covering the tip-ends of strips of cigarette-paper with gold-foil, the combination, of an oscillating knife-holder, a horizontal shaft for said holder, a knife attached to said holder, and means for shifting the knife-holder laterally on its shaft. 80

4. In an apparatus for covering the tip-ends of strips of cigarette-paper with gold-leaf, the combination of an intermittently-oscillating and laterally-shiftable knife-holder, a knife attached to the same, a horizontal table, means for feeding a layer of gold-leaf with its underlying strip over said table, a roller at the outer end of the knife-carrying arm or holder, a reciprocating carriage moving over said table in a direction opposite to the gold-leaf, and provided with guide-rollers and an inclined inner end, means for feeding a strip of cigarette-paper over the rollers of said carriage, means for supplying an adhesive coating to 90 the tip-end of the strip of cigarette-paper, and an intermittently-actuated pressure-plate for transferring the gold-foil to said strip of cigarette-paper. 95

5. In an apparatus for covering the tip-ends of strips of cigarette-paper with gold-foil, the combination of a horizontal table, an intermittently-oscillating and laterally-shiftable leaf-severing knife, means for feeding the gold-leaf with its underlying 100 layer of paper over said table, a horizontally-reciprocating carriage extending over the table, guide-rollers on said carriage, means for moving a strip of cigarette-paper over said rollers, fixed guide-rollers for the 110 cigarette-paper forming with the movable guide-rollers a bight in the cigarette-paper, and an intermittently-actuated pressure-plate for transferring the gold-foil severed by the knife to the non-movable bight of 115 cigarette-paper. 120

6. In an apparatus for covering the tip-ends of strips of cigarette-paper with gold-foil, the combination, of a horizontal table, means for intermittently-oscillating the 125 same, an intermittently-oscillating and laterally-shiftable leaf-severing knife, means for feeding the gold-leaf with its underlying layer of paper over said table, a horizontally-reciprocating carriage extending over 130

the table, guide-rollers on said carriage for guiding a strip of cigarette-paper, means for feeding said strip over said table, and fixed guide-rollers forming with the movable guide-rollers the cigarette-paper into a bight for intermittently transferring the severed pieces of gold-leaf to the cigarette-paper.

7. In an apparatus for covering the tip-ends of strips of cigarette-paper with gold-foil, the combination, of a horizontal table, a cutting-knife, means for feeding the gold-leaf with its underlying layer of paper over the table, a horizontally-reciprocating carriage provided with guide-rollers, means for supplying a continuously-movable strip of cigarette-paper over the guide-roller on the carriage, fixed guide-rollers forming a loop or bight in the strip of cigarette-paper in connection with the reciprocating guide-rollers, means for intermittently supplying an adhesive to the ingoing continuously-moving strip of cigarette-paper, and means for intermittently-transferring the severed gold-leaf to the loop or bight formed in the cigarette-paper.

8. In an apparatus for the manufacture of cigarettes with mouthpieces having covering material, a cutting table, means for leading a compound strip consisting of the said covering material and underlying paper across said cutting table, a knife having free vertical movement for cutting said covering material, and means for drawing said knife across said compound strip, whereby the weight of said knife determines the depth of the cut, so as to sever only said covering material.

9. In an apparatus for the manufacture of cigarettes with mouthpieces having covering material, a cutting table, means for leading a compound strip consisting of the

said covering material and underlying paper across said cutting table, a knife having free vertical movement for cutting said covering material, means for drawing said knife across said compound strip, and means for regulating the downward pressure upon said knife, so as to sever only said covering material.

10. In an apparatus for the manufacture of cigarettes with mouthpieces having covering material, a cutting table, means for leading a compound strip consisting of the said covering material and underlying paper across said cutting table, a cutting knife having a free vertical movement, means for drawing said cutting knife across said compound strip, means for regulating the downward pressure upon said knife, whereby it severs only the covering material, and means for intermittently raising said cutting knife from the compound strip, so as to permit the feed thereof.

11. In an apparatus for the manufacture of cigarettes, a pressing-table, means for continuously feeding a compound strip of covering material to and away from said pressing-table, a reciprocating carriage having rollers mounted thereon, the said rollers having their axes spaced apart in a direction parallel to the line of movement of the strip, and having a portion of the pressing-table intermediate their axes, said strip of material being led over said rollers and the intermediate portion of the pressing-table.

In testimony, that I claim the foregoing as my invention, I have signed my name in presence of two subscribing witnesses.

JOHANN CARL MÜLLER.
